UNITED STATES PATENT OFFICE.

REA P. W. WRIGHT, OF WASHINGTON, DISTRICT OF COLUMBIA, ASSIGNOR TO JOHN FRANCIS HEMENWAY, OF NEW YORK, N. Y.

AUTOMATIC PRESSURE-ROLL RELEASE FOR CLOTHES-WRINGERES.

1,224,053.

Specification of Letters Patent. Patented Apr. 24, 1917.

Application filed October 22, 1916. Serial No. 127,902.

To all whom it may concern:

Be it known that I, REA P. WRIGHT, a citizen of the United States, residing at Washington, in the District of Columbia, have invented certain new and useful Improvements in Automatic Pressure-Roll Releases for Clothes-Wringeres, of which the following is a specification, reference being had therein to the accompanying drawing.

10 This invention relates to certain new and useful improvements in an automatic pressure roll release for a clothes wringer and consists in providing a clothes wringer with a fixed top bar having slidably mounted boxes normally held in position by pivoted latches arranged to be engaged by operating levers carried by the frame, when said levers are moved on the pivots, so that the latches will be moved out of engagement 15 with the boxes in order to allow the boxes to move vertically within the top bar to release the pressure means.

Another object of my invention is to provide the boxes with notches which are engaged by pivoted latches mounted in cut-away portions formed in the ends of the top bar in order to construct a wringer with a pressure roll release in which the parts are arranged below the upper surface of the top 20 bar.

Other and further objects and advantages of the invention will be hereinafter set forth and the novel features thereof defined by the appended claims.

3 In the drawings,

Figure 1 is a side elevation of a clothes wringer partly in section showing the application of my improved construction of release thereto;

40 Fig. 2 is a perspective view of my improved construction of release detached therefrom, and

Fig. 3 is a horizontal section taken through the end portion of the top bar 45 showing the arrangement of the pivoted latch box and bearing sleeve.

Like numerals of reference refer to like parts in the several figures of the drawing.

In the drawing, 1 indicates a wringer 50 frame provided with slotted side bars 2 carrying pressure rolls 3 and 4 provided with the usual shafts 5 and 6 mounted in suitable bearings arranged within the slotted side bars, the upper bearings carrying spring 55 supports 7 upon which pressure springs 8

are mounted engaged by bearing plates 9 carried by a pressure bar 10.

The frame 1 is provided with a fixed top bar 11 secured within the slotted side bars 2 at their upper ends, said top bar having 60 vertical bores formed therein adjacent its ends which register with notches formed in the ends of the side bars in which are mounted pivoted latches 12 adapted to extend through slots 14 formed in bearing 65 sleeves 15 secured within the bores of the top bar and into notches 16 formed in internally threaded boxes 17 which are slidably mounted within the bearings 15 in such a manner that the boxes are prevented from 70 rotating. The boxes are provided with lugs 18 extending into the slots 19 formed in the bearings 15 for limiting the upward movement thereof as clearly shown in Fig. 2. Mounted within the internally threaded 75 boxes 17 are pressure screws 20 adapted to engage the bearings 9 of the pressure bar 10 for adjusting the pressure on the pressure rolls.

The latches 12 are mounted in the cut-away portions and extend outwardly beyond the end portion thereof in the path of travel of the angular levers 22 which are pivotally mounted on studs 23 carried by the side bars 2 of the wringer frame in such a manner 80 that when the levers 22 are swung on their pivots, the latches 12 will be engaged thereby so as to oscillate said latches in order to move the inner ends thereof out of the notches 16 of the boxes 17. As the latches 90 12 are moved out of the notches 16 of the boxes 17, the boxes will be released so as to allow the same to move within the top bar in order to release the pressure means.

In order to provide means for automatically rocking the levers 22 on their pivots, I arrange the lower end portions 24 thereof in the path of travel of the upper pressure roll shaft 6 when said shaft is moved vertically by the separation of the pressure rolls 3 100 and 4.

From the foregoing description, it will be seen that I have provided a clothes wringer with slidably mounted non-rotatable boxes carrying pressure screws for adjusting the 105 pressure means which are normally held in predetermined position within the top bar of the wringer frame by pivoted latches mounted in cut-away portions of the top bar which are engaged by levers actuated by one 110

of the pressure roll shafts when said pressure rolls are separated.

I claim:

1. A clothes wringer, comprising a frame having pressure rolls and pressure means for said rolls mounted therein, a top bar fixed in said frame having slidably mounted non-rotatable boxes at the ends thereof, said top bar having cut-away portions, pivoted latches mounted in the cut-away portions for holding said boxes in predetermined position within said top bar, levers mounted on the side bars of said frame having portions arranged in the path of travel of one of said pressure roll shafts on the separation of said rolls, said latches having portions arranged in the path of travel of said levers for moving said latches out of engagement with said boxes for releasing said pressure means.
2. A clothes wringer, comprising a frame having pressure rolls and pressure means for said rolls mounted therein, a top bar fixed in said frame having vertically disposed bores at each end and cut-away portions communicating with said bores, bearing sleeves fixed in said bores having slots registering with the cut-away portions of said top bar, non-rotatable boxes slidably mounted in said bearing sleeves having notches, pivoted latches mounted in the cut-away portions of the top bar adapted to extend into the notches in said boxes for holding said boxes in predetermined position within said frame, and levers pivotally mounted on the side bars engaging said latches for moving said latches out of the notches of said boxes for releasing said boxes on the separation of said pressure rolls.
3. A clothes wringer, comprising a frame having pressure rolls and pressure means for said rolls mounted therein, a top bar fixed in said frame, non-rotatable slidably mounted pressure carrying boxes carried by said top bar, pressure screws mounted in said boxes for adjusting said pressure means, said top bar having cut-away portions at its ends, pivoted latches mounted in said cut-away portions, said boxes having notches adapted to receive said latches for holding said boxes in predetermined position within said frame, pivoted levers mounted on the side bars of said frame adapted to move said latches out of said notches for releasing said boxes, said levers having portions arranged in the path of travel of one of the pressure roll shafts on the separation of said rolls.
4. A clothes wringer, comprising a frame having pressure rolls and pressure means for said rolls, slidably mounted non-rotatable boxes arranged in said frame, pivoted latches mounted in said frame for holding said boxes in predetermined position therein, and means actuated by the abnormal separation of said pressure rolls for moving said latches in position to release said boxes.
5. A clothes wringer, comprising a frame having pressure rolls and pressure means for said rolls, slidably mounted non-rotatable boxes carried by said frame, pivoted latches mounted in said frame for holding said boxes in predetermined position, and levers engaging said latches on the abnormal separation of said pressure rolls for allowing said boxes to move within said frame to release said pressure means.
6. A clothes wringer, comprising a frame having pressure rolls and pressure means for said rolls mounted therein, a top bar fixed in said frame, slidably mounted non-rotatable boxes seated in said top bar, said top bar having cut-away portions, pivoted latches mounted in said cut-away portions for holding said boxes in predetermined position and levers actuated by the abnormal separation of said pressure rolls engaging said latches for releasing said boxes.

In testimony whereof I hereunto affix my ⁹⁰ signature.

REA P. WRIGHT.
